UNITED STATES PATENT OFFICE.

CHARLES BUSS AND IVAN C. W. BUSS, OF PITTSBURGH, PENNSYLVANIA.

RAILROAD-TIE.

1,342,420.

Specification of Letters Patent. Patented June 8, 1920.

Application filed March 9, 1920. Serial No. 364,557.

To all whom it may concern:

Be it known that we, CHARLES BUSS and IVAN C. W. Buss, citizens of the United States, residing at Pittsburgh, in the county of Allegheny and State of Pennsylvania, have invented certain new and useful Improvements in Railroad-Ties, of which the following is a specification.

This invention relates to new and useful improvements in railroad ties, and has for its objects to provide a tie of the character stated, in the manner as hereinafter set forth, which is substantially constructed of the combination of wood and metal thereby providing for the resiliency in the former and the permanency in the latter, which provides novel means for its being firmly and fixedly embedded in the roadbed, and which embodies tie plates permanently connected therewith.

Further objects of the invention are to provide a device of the class described, which is comparatively simple in its construction and arrangement, strong, durable and efficient in its use, and inexpensive to manufacture.

To the accomplishment of these and such other objects as may hereinafter appear, the invention consists of the novel construction, combination and arrangement of parts herein specifically described and illustrated in the accompanying drawing wherein is shown an embodiment of the invention, but it is to be understood that the device shown is merely illustrative and that various changes in the form, proportion and minor details of construction may be resorted to which come within the scope of the claims hereunto appended.

In the drawing forming a portion of this specification and wherein like numerals of reference designate corresponding parts throughout the several views:

Figure 1 is a perspective view of a tie in accordance with the invention, and showing a section of rail mounted thereon.

Fig. 2 is a perspective view of the metal channel member included in the invention.

Fig. 3 is a perspective view of the tie plate.

Referring in detail to the drawing 1 indicates the metal channel member consisting of the bottom portion 2 and the integrally formed vertical flanges 3 and 4, respectively.

The flanges 3 and 4, adjacent each end thereof, are formed with a cut-out portion 5 for the purpose hereinafter fully set forth.

A block of wood 6, commensurate in thickness to the depth of the channel member 1, is securely mounted in each end of the latter, by means of the nuts 7 and bolts 8, 60 which latter extend through suitable apertures 9, in the flanges 3 and 4, provided therefor.

The bottom portion 2, of the channel member 1, extends only along that portion 65 thereof which is covered by each of the wooden blocks 6; the bottom portion therebetween being cut out or entirely open, as indicated at 10. The ends 11, of the flanges 3 and 4, extend slightly beyond the outer 70 ends of the blocks 6, and the outer edges of the bottom portions 2. This open construction of the bottom portion in conjunction with the projecting ends 11, of the flanges 3 and 4, together with the perforations 12, in 75 the bottom portion 2, permits the tie to be immovably fixed in the roadbed by ballast.

The tie plate used in connection with our improved tie comprises a flat plate 13 having a depending flange 14 formed integral with 80 each side edge thereof and extending at right angles thereto. The tie plates are securely fixed to the blocks 6, with the depending flanges 14 extending into the cut-out portions 5 of respective flanges 3 and 4 of 85 the channel member 1, by means of the nuts 15 and bolts 16, which latter extend through apertures 17 in the flanges 14 and through the blocks 6.

The tie plate is further secured to each 90 of the blocks 6 by the spikes 17 which are driven into the block 6 through the apertures 18, one of which is formed in each end of the plate 13. The plate 13 is provided with a pair of vertically disposed lugs 19 95 and 20, positioned diagonally with respect to each other on the said plate. The rail 21 is adapted to be placed intermediate of the lugs 19 and 20 upon the tie plate, and when the former is secured to the tie and 100 plate by means of the spikes 22, which pass through the diagonally disposed apertures 23 and 24 in the plate 13, the lugs 19 and 20 in conjunction with the spikes 22 prevent lateral displacement of the rail 21 upon the 105 tie plate.

It will here be noted that the manner of securing, the tie plate to the block 6 and the latter in the channel member 1, will not only entirely eliminate the liability of splitting the blocks 6 when spikes are driven therein, and substantially reinforce the said

blocks, but will almost completely cover the same, thereby in a measure preventing decay from exposure.

It is readily apparent that when the blocks deteriorate from use and exposure the old metal parts of the tie can be conveniently provided with a new pair of wood blocks, providing a substantially new tie at little expense.

10 What we claim is:

1. A rail tie comprising a metallic channel shaped member having each of its sides cut away in proximity to each end, a cushioning block arranged in said member at each end, a tie plate mounted on each block and having depending flanges positioned against the sides of said block at the cutaway portions of the sides of said member, and means for securing the blocks and tie

20 plates to said member.

2. A rail tie comprising a metallic channel shaped member having each of its sides cut away in proximity to each end, a cushioning block arranged in said member at each end, a tie plate mounted on each block and having depending flanges positioned against the sides of said block at the cutaway portions of the sides of said member, and means for securing the blocks and tie plates to said member.

30 said member between said blocks having its bottom cut away.

3. A rail tie comprising a metallic channel shaped member having each of its sides cut away in proximity to each end, a cushioning block arranged in said member at each end, a tie plate mounted on each block and having depending flanges positioned

against the sides of said block at the cutaway portions of the sides of the said member, transversely extending bolts at each end 40 of said member for securing said blocks in position, nuts on said bolts, and means for securing the tie plates to the blocks.

4. A rail tie comprising a metallic channel shaped member having each of its sides 45 cut away in proximity to each end, a cushioning block arranged in said member at each end, a tie plate mounted on each block and having depending flanges positioned against the sides of said block at the cutaway portions of the sides of said member, and means for securing the blocks and the tie plates to the said member, said tie plate having upwardly bent portions to provide a pair of diagonally disposed lugs. 50

5. A rail tie comprising a metallic channel shaped member having each side thereof of cut away in proximity to each end, a wooden cushioning block mounted in said member at each end, said member having its 60 bottom between said blocks cut away, means extending through the sides of said member and through said blocks for connecting them together, a tie plate having diagonally disposed upwardly extending lugs and a pair 65 of depending flanges mounted on each block, and means extending through said flanges and said blocks for securing the tie plates to the blocks.

In testimony whereof we affix our signatures. 70

CHARLES BUSS.
IVAN C. W. BUSS.
